[57] ABSTRACT

A lift truck having a three-stage lift mast comprising

three mast sections, each such section including two uprights positioned at a horizontal distance from each other, has the two uprights of an outer section secured to the chassis of the truck and U-shaped with the U-openings facing each other. An intermediate and an inner section, the latter one provided with a load carriage, are telescopically displaceable in said outer section. On each upright of the intermediate section and inside the flanges of the uprights of the outer section are two vertical rows of guide rolls in the same vertical plane. The running surfaces of the rolls of the first row are outwardly in engagement with the inner side of the first flange of the upright of the outer section and the running surfaces of the rolls of the second row are outwardly in engagement with the inner side of the second flange of the same upright, whereas the running surfaces of the rolls of both rows at the same time are inwardly in engagement with the outer sides of a flange, belonging to the upright of the inner section and inserted between the two rows of rolls. The purpose is to make the horizontal extension of the mast perpendicular to the drive direction of the truck as small as possible.

LIFT TRUCKS HAVING A THREE-STAGE LIFT MAST

The present invention relates to a lift truck having a three-stage lift mast comprising three mast sections, each such section including two uprights positioned at a horizontal distance from each other, the two uprights of an outer section being U-shaped with the U-openings facing each other, said outer section being secured to the chassis of the truck, whereas an intermediate and an inner section are telescopically displaceable in the outer section, said inner section being provided with a load carriage.

Such masts are relatively wide due to the fact that the uprights of the three sections are positioned side by side, which decreases the sight forward. Furthermore the material of these sections from the point of view of strength and rigidity is unsufficiently utilized as usually the cross section of said uprights is the same for all three sections.

It is a principal object of the present invention to make the horizontal extension of the mast perpendicular to the drive direction of the truck as small as possible and to redistribute the material between the uprights so that it is better utilized.

This and other objects and advantages of the invention will be apparent to those familiar with the art when the following description is read in conjunction with the drawings, in which:

FIG. 1 is a front view of the lift mast in a wholly extended position,

FIG. 2 is a cross-sectional view on the line II—II in FIG. 1,

FIG. 3 is a cross-sectional view on the line III—III in FIG. 1,

FIG. 4 shows the lift mast according to FIG. 1 as seen from the left,

FIG. 5 is a front view of the same lift mast in a retracted position,

FIG. 6 is a cross-sectional view on the line VI—VI in FIG. 5, and

FIG. 7 is a cross-sectional view in an enlarged scale on the line VII—VII in FIG. 5.

The lift mast comprises three mast sections inserted in each other, an outer 1, an intermediate 2 and an inner 3, of which the outer section 1 is secured to the chassis of the truck. A load carriage 4 (FIGS. 2 and 3) is movable up and down the inner section 3, said load carriage 4 being provided with rulers 5 and 6, which carry forks 7. The load carriage 4 includes two columns 17 positioned parallel to and at a distance from each other. These columns 17 are connected by means of the rulers 5 and 6.

How the sections are arranged and supported in each other is best shown in FIG. 7, which as a front view and in cross-section discloses the left uprights of the three sections, and in FIG. 2 and 4.

The outer section 1 consists of two U-shaped, vertical and parallel uprights 8 having their U-openings facing each other. The uprights 8 are placed at a distance from each other and are connected by means of cross bars 9 and 10.

In the outer section 1 runs the intermediate section 2, which consists of two vertical and parallel uprights 11, positioned at a distance from each other and connected through cross bars 12 and 13. In the intermediate section 2 runs the inner section 3, which consists of two vertical and parallel uprights 14, positioned at a

distance from each other and connected through cross bars 15 and 16.

Each of the two uprights 11 of the intermediate section 2 is provided with a number of guide rolls 18 and 19, arranged in two rows in the length direction of the uprights, these rolls having for their purpose to guide the three sections 1, 2 and 3 in relation to each other. The guide rolls 18 and 19 are rotatably mounted about shafts 20, secured to the uprights 11 of the intermediate section 2 and are active between the flanges 21 and 40 of the U-shaped uprights 8 of the outer section 1 and an intermediate flange 22 of the uprights 14 of the inner section 3.

At an unbalance of the mast the sections tend to move in relation to each other in the axial direction of the rolls 18 and 19. This is prevented thereby that the flanges 21 and 40 of the uprights 8 are provided with grooves 23, the edges of which work against the two sides 25 of the rolls 18 and 19. Furthermore the uprights 14 are provided with shoulders 26 working against the inner sides 25 of the rolls 18 and 19. The less the mast is extended the more rolls will work against the outer and inner sections, which means that the three sections cooperate to decrease the bending of the mast. By inclining the sides 25 of the rolls, the edges 24 of the grooves 23 and the shoulders 26 from the radial direction of the rolls, there is ensured a line contact and an ideal rolling off.

The movement of the load carriage 4 in the inner section 3 is guided by two pairs of rolls 27 (FIG. 3 and 7), an upper pair and a lower pair, which run against a rear flange 29 of the uprights 14, said rolls 28 taking the forces which arise when the load carriage 4 is in unbalance.

From the above it is evident that the uprights of the sections to a large extent are built in into each other and totally they are not wider than a normal two-stage mast. The cross-sections of the uprights are also given such dimensions that the material in them all is well utilized from the point of view of both strength and rigidity. Through this redistribution of the material between the uprights included in the mast, for a given building length of the mast it is achieved, when the mast is retracted, a considerable decrease of the width of the mast, and, when the mast is fully extended, a bending of the mast which is about half as large as for conventional three-stage masts. Furthermore the rigidity against bending, when the mast is only partially extended, is further improved as the guide rolls force the uprights of the sections to cooperate. The three-stage masts known before are as a rule provided with special rolls for the side guiding, which means that more surfaces on the uprights of the sections must be machined in relation to what is necessary at the mast according to the present invention.

The movement upwards of the load carriage 4 is achieved by means of a hydraulic lift cylinder (FIG. 1 and 2), including an outer tube 30, an intermediate tube 31 and a piston-rod 32, and furthermore of an oil-supply pipe 33 with connection nipple 34 and a chain arrangement including two lift chains 35. The lift cylinder is of the free lift cylinder type and is positioned between the lower cross bar 12 of the intermediate section 2 and the upper cross bar 16 of the inner section 3. The oil supply pipe 33 is secured to the lower cross bar 9 of the outer section 1 and passes via a sealing the lower cross bar 12 of the intermediate section 2 and

into the tube-shaped piston-rod 32. The chains 35 with their one ends are secured to the upper cross bar 10 of the outer section 1, run over guide rolls 36 on the lower cross bar 12 of the intermediate section 2, over guide rolls 38 on the upper side of the movable outer tube 30 of the hydraulic cylinder and to their other securing points in the load carriage 4.

When the oil is pressed into the lift cylinder the movable outer tube 30 is first lifted from its lower to its upper position, the load carriage 4 thereby, due to the transmission ratio being lifted the double distance or to its upper position in the inner section 3. After that the cylinder begins to press the intermediate section 2 and the inner section 3 apart and at the same time the intermediate section 2 is lifted due to the securing of the chains to the outer section 1. The intermediate section 2 is lifted as much in the outer section 1 as the inner section 3 is lifted in the intermediate section 2. During this part of the lift the load carriage 4 is unmovable in its upper position in the inner section 3 at the same time as this is lifted at a double speed in relation to the speed at which the intermediate section 2 is lifted in relation to the unmovable outer section 1. During a lowering operation of the mast the function is reversed, i.e. when oil is leaving the lift cylinder the sections are lowered, after which also the load carriage is lowered in relation to the inner section 3.

Having described my invention, I claim:

1. A lift truck having a three-stage lift mast comprising:
an outer mast section, an intermediate mast section and an inner mast section, with said intermediate and said inner section being telescopically displaceable lengthwise within said outer section; each of said mast sections including a pair of upright members horizontally spaced apart with each member having a base section and a pair of flanges extending from one side of said base section form-

5

ing said member in a U-shaped configuration, with the flanges of one of the members of each of each pair of members facing toward the other member of said pair;

a third flange extending from the base section of each of said upright members of said inner mast section on the side thereof opposite the side from which said pair of flanges extend; means securing said outer section to said lift truck; a load carriage mounted on said inner section; and a first and a second vertical row of guide rolls with at least two rolls in each of said rows, said rolls having running surfaces and each being rotatably mounted upon said base section of said intermediate mast section positioned in the same vertical plane; the running surfaces of the rolls of said first row being outwardly in engagement with the inner side of one flange of said outer section upright members; the running surfaces of the rolls of said second row being outwardly in engagement with the inner side of the other of said flanges of said outer section upright members;

the running surfaces of the rolls of both said first and said second row being simultaneously inwardly in engagement with one side, respectively, of said third flange of said inner sections, with said third flange of said inner sections being located between said rows of guide rolls;

whereby horizontal extension of said mast perpendicular to the drive direction of said truck is minimized.

2. A lift truck according to claim 1 wherein the inner sides of both said flanges of said upright members of said outer sections, and wherein each side of said third flange of said upright members of said inner sections, are provided with shoulders located for cooperative engagement with the sides of said rolls.
